UNITED STATES PATENT OFFICE.

JULIUS L. KNIEPER, OF GRAND RAPIDS, MICHIGAN.

CHAIR.

SPECIFICATION forming part of Letters Patent No. 379,959, dated March 27, 1888.

Application filed May 7, 1887. Serial No. 237,475. (No model.)

To all whom it may concern:

Be it known that I, JULIUS L. KNIEPER, a citizen of the United States, residing at the city of Grand Rapids, in the county of Kent 5 and State of Michigan, have invented certain new and useful Improvements in Chairs, of which the following is a specification.

My invention relates to a chair having rockers adapted to be adjusted vertically within 10 the chair-legs and to be locked in such positions by the mechanism hereinafter fully described; and the object of my invention is to adapt the chair to be used as a rocking-chair when its rockers are lowered and as an ordinary chair when the rockers are raised. These 15 objects I accomplish by means of the mechanism illustrated in the accompanying drawings, in which—

Figure 1 is a perspective view of my invention 20 in such a position as to show the device for attaching the chair-seat to the bottom of the chair. Fig. 2 is a side elevation of one of my rockers, showing my preferred method of attaching the same to the legs of the chair. Fig. 3 is a side elevation of the rocker with 25 two of the chair-legs in the position they occupy with reference to the rocker when the chair is not used as a rocking-chair; and Fig. 4 is a side elevation of the same parts shown in 30 Fig. 3, with the rocker secured in position to be used with the chair as a rocking-chair. The attachment and adjustment of the two rockers are identical.

Similar letters refer to similar parts throughout 35 the several views.

A is the bottom of the seat of the chair permanently attached to the upper ends of the chair-legs.

B is the aperture through the bottom A of 40 the ordinary form.

F is a detachable seat provided with legs L L.

G G are two swinging buttons attached to the legs, adapted to turn beneath the bottom A, and thereby attach and hold the seat F to 45 the chair and to allow for its ready removal.

The chair-legs are slotted at the bottom, as

shown at K K K K, for the reception of the rockers C C. In Fig. 1 the rockers are shown in the legs in the position for use.

I I I are bolts, pins, or screws, each pin 50 passing through the chair-leg and also through one of the slots E. The slots E E E E are made of such size that the pins will move freely in each slot, and they are of such shape that the pins may be locked in the upper part 55 of the slots, thereby securing the rockers in the position shown in Figs. 1 and 4.

D D are eccentric-levers adapted to turn on bolts or pins, and when turned down, as shown in Figs. 1 and 4, to press against the leg of the 60 chair and lock the pins in the upper part of the slots E. In the drawings I have shown but two of these eccentric-levers, as one lever for each rocker is all that is required.

I am not aware that any chair has been made 65 prior to my invention with slotted legs for the reception of the rockers and of such size as to allow the rocker to be adjusted vertically within the slot in order to convert the chair from an ordinary chair into a rocking-chair at 70 pleasure.

Having thus described my invention, what I claim to have invented, and desire to secure by Letters Patent, is—

1. In a chair of the class described, the combination of the legs having vertical slots and pins I I, the rockers provided each with the openings E E, said rockers adapted to be vertically adjusted in the slots in the rockers, and the pins adapted to engage with the upper 80 part of the openings E E in the rockers, substantially as described.

2. In a chair of the class described, the combination of the vertically-slotted legs, the pins I I, the rockers provided with openings E E, 85 the eccentric-levers D D, for locking the rockers, substantially as described.

JULIUS L. KNIEPER.
